UNITED STATES PATENT OFFICE.

JOHN R. McGRANIGHAN, OF PHILADELPHIA, PENNSYLVANIA.

DESIGN FOR A HOLDER FOR A CURLING IRON.

Application filed May 31, 1927. Serial No. 22,250. Term of patent 7 years.

To all whom it may concern:

Be it known that I, JOHN R. McGRANIGHAN, a citizen of the United States, residing at Roxborough, Philadelphia, in the county of Philadelphia and State of Pennsylvania, have invented a new, original, and ornamental Design for Holders for Curling Irons, of which the following is a specification, reference being had to the accompanying drawing, forming part thereof.

In the drawing—

Fig. 2 is a vertical section thereof taken on the line 2—2 of Fig. 1.

I claim:

The ornamental design for a holder for a curling iron, as shown.

JOHN R. McGRANIGHAN.
